Patented Apr. 6, 1915.

UNITED STATES PATENT OFFICE.

EARL D. PEERSTONE, OF CHICAGO, ILLINOIS.

VALVE FOR RADIATORS.

1,134,415.

Specification of Letters Patent. Patented Apr. 6, 1915.

Application filed April 1, 1914. Serial No. 828,682.

To all whom it may concern:

Be it known that I, EARL D. PEERSTONE, a citizen of the United States, residing in Chicago, in the county of Cook and State of Illinois, have invented a new and useful Improvement in Valves for Radiators, of which the following is a specification, reference being had to the accompanying drawings, forming part thereof.

10 This improvement is designed for the purpose of providing a quicker and more convenient means for controlling the supply of steam to the radiator. To accomplish this purpose this valve is designed to be operated by a person's foot. A downward push applied to the head of the valve stem moves the valve to a closed position, in which it is held fast by a spring actuated friction grip. To open the valve this friction grip is released by a slight touch with the foot, causing a downward and outward movement of the friction grip, in which position it clears the valve stem and permits the valve to spring open. Both movements are practically instantaneous.

Figure 1, is a vertical section through the valve, showing the parts in closed position. Fig. 2, is a vertical section through the valve, showing the parts in open position. Fig. 3, is a detail elevation, showing the connection of the friction grip to its support. Fig. 4, is a view, showing a modification of the upper portion of the valve stem, etc. Fig. 5, is a view, showing another modification of the upper portion of the valve stem, etc.

The valve consists of a casing, 1, forming a chamber, 1^a, having an opening, 1^b, for connection to the steam supply, and having an opening, 1^c, for connection to the radiator. A plug, 2, closes the opening in the top of the casing, through which the valve is admitted, and forms a guide for the valve stem, 3, to the lower end of which is secured a valve disk, 4, by means of a valve hanger, 4^a, which is fitted around the enlarged end, 3^a, of the valve stem. The plug, 2, also supports a tubular casing, 5, for inclosing a helical spring, 6, which seats on top of the plug, 2. The casing, 5, also serves as a post for supporting a bonnet, 7, which has a recess in its upper face for receiving the packing, 9, which is forced into contact with the valve stem by the packing nut, 8. A cover, 10, is adjustably mounted on the packing nut, 8, and serves as a seat for a bumper 15, and posts, 11. A disk shaped friction grip, 12, having an opening through

the center of it through which the valve stem passes, is pivoted to the posts by means of a pin, 13, and is maintained in operative engagement with the valve stem, 3, by means of a small spiral spring, 14, which serves to elevate the free side of the friction grip, thus bringing the edge of the opening in the friction grip against the valve stem. A cap or tread, 16, is attached to the upper end of the valve stem, 3, and serves as a tread for the foot. A collar, 17, attached to the valve stem serves to engage the spring, 6, and compresses same when the valve stem is lowered, being returned to its original position when the valve stem is released.

In operation the downward pressure of the foot on the head or tread of the valve stem moves the stem inward until the valve seats and closes the opening, 1^b. While the downward pressure is being exerted the friction grip offers no resistance, but as soon as the downward movement ceases the friction grip being in engagement with the valve stem prevents the return or upward movement of the valve stem. To release the valve stem and open the valve it is necessary to exert a slight downward pressure on the free side of the friction grip, with the foot, which moves the friction grip slightly outward and away from the valve stem, permitting same, by means of the spring 6, to spring open. The plug, 2, has a recess formed in the central part of its lower portion, said recess being substantially shaped like a truncated cone and is designed to receive the upper portion of the valve hanger, 4^a, the edges of which are beveled, both the edges of the hanger and the corresponding faces of the cone shaped recess in the plug being ground true, so that when they are in engagement with each other they will form a tight joint and prevent the escape of steam from the chamber, 1^a. This feature of construction is provided so that the packing may be changed while the radiator is in service. The cover, 10, is attached to the packing nut, 8, by a threaded connection, so that it may be adjusted to the same relative position to the radiator at all times, regardless of the position of the packing nut, 8, which may vary and thus affect the position of the cover. This adjustment of the cover is desirable so that the spring actuated friction grip supported by the cover may always be maintained in a position in which it may easily be released by the foot, which position will generally be on the side away from the

radiator as indicated in the drawings. The bumper, 15, is provided to limit the downward movement of the friction grip when it is touched with the foot. In Fig. 1 the friction grip is shown in position to engage the valve stem and maintain the valve closed. In Fig. 2 the friction grip is shown in position to clear the valve stem and permit the valve to open. If desired, the upper portion 10 of the valve stem, 3^b, shown in Fig. 4, where it is engaged by the friction grip, may be slightly tapered inward in an upward direction. With this construction the friction grip would operate as a positive lock against 15 the upward movement of the valve stem, as it would be within the line of travel of the constantly enlarging section of the valve stem. While the possibility of a friction grip of the ordinary type slipping is remote, 20 the construction shown in Fig. 4 would eliminate any possibility of such slipping. Also, if desired, the adjustable thimble, 18, shown in Fig. 5, may be employed to establish a fixed position in which the valve will be 25 closed and the friction grip operative. This is accomplished by using a thimble constituted of two conic shaped sections, tapering inwardly in opposite directions from a common base, indicated at a point marked "X"; 30 the spring actuated friction grip being inoperative while engaging the lower conic shaped section and offering no opposition to the upward or return movement of the valve stem until the valve stem has made a full 35 stroke downward, and thereby brought the friction grip into engagement with the upper conic section, just above the point "X", in which position it holds the valve closed, until it is released in the ordinary way. The 40 thimble is adjustable, so that its position on the valve stem may be changed to suit the position of the packing nut 8, and that of the cover, 10, either or both of which would affect the relation of the thimble to the friction grip.

Having thus described my invention, I claim:—

1. A valve device, comprising a casing, a valve stem mounted in the casing, yielding 50 resistance means for opposing the inward movement of the valve stem, a friction grip for engaging the valve stem, a packing nut, and a support for the friction grip having an adjustment for regulating the position 55 of the friction grip with relation to the packing nut.
2. A valve device, comprising a casing, a valve stem mounted in the casing, yielding resistance means for opposing the inward 60 movement of the valve stem, a tread mounted upon the upper end of the valve stem, a friction grip for engaging the valve stem, a packing nut, and a support for the friction

grip having an adjustment for regulating the position of the friction grip with relation to the packing nut. 65

3. A valve device, comprising a casing, a valve stem mounted in the casing, a bonnet having a recess for packing, a packing nut, yielding resistance means for opposing the 70 inward movement of the valve stem, a friction grip for engaging the valve stem, and an adjustable support for the friction grip.

4. A valve device, comprising a casing, a valve stem mounted in the casing, a valve 75 disk attached to the lower end of the valve stem, a thimble attached to the upper portion of the valve stem, having a conic shaped upper section, and a catch for engaging the conic shaped upper section of 80 the thimble when the valve is closed.

5. A valve device, comprising a casing, a valve stem mounted in the casing, a valve disk attached to the lower end of the valve stem, a thimble attached to the upper portion 85 of the valve stem, having upper and lower conic shaped sections, tapering inwardly in opposite directions from a common base, and a spring actuated catch for engaging the upper conic shaped section of 90 the thimble when the valve is closed.

6. A valve device, comprising a casing, a valve stem mounted in the casing, a valve disk attached to the lower end of the valve stem, a thimble attached to the upper part 95 of the valve stem having upper and lower conic shaped sections, tapering inwardly in opposite directions from a common base, yielding resistance means for opposing the inward movement of the valve stem, and a 100 catch for engaging the upper conic shaped section of the thimble when the valve stem has completed its inward stroke.

7. A valve device, comprising a casing, a valve stem having a tapering upper portion 105 and a cylindrical lower portion, and a friction grip for engaging the tapered portion of the valve stem.

8. A valve device, comprising a casing, a valve stem having a tapered upper portion, 110 a valve disk attached to the lower end of the valve stem, and a spring actuated catch for engaging the tapered portion of the valve stem.

9. A valve device, comprising a casing, a 115 valve stem having a tapered upper portion, yielding resistance means for opposing the inward movement of the valve stem, and a friction grip for engaging the valve stem.

In testimony whereof I have hereunto set 120 my hand at Chicago, Illinois, this 30th day of March, 1914.

EARL D. PEERSTONE.
